UNITED STATES PATENT OFFICE

150,638

DESIGN FOR A DOLL OR SIMILAR ARTICLE

Louise G. McDonald, Los Angeles, Calif.

Application November 6, 1946, Serial No. 134,541

Term of patent 14 years

(Cl. D34—4)

To all whom it may concern:

Be it known that I, Louise G. McDonald, a citizen of the United States of America, residing at Los Angeles, in the county of Los Angeles and State of California, have invented a new, original, and ornamental Design for Doll or Similar Article, of which the following is a specification, reference being had to the accompanying drawing, forming a part thereof.

Fig. 1 is a front elevational view of a doll showing my new design.

Fig. 2 is a side elevational view of the doll.

Fig. 3 is a rear elevational view of the doll.

I claim:

The ornamental design for a doll or similar article, as shown.

LOUISE G. McDONALD.
